We claim the ornamental design for a mobile office booth, as shown and described.

DESCRIPTION

FIG. 1 is a perspective view of a mobile office booth showing our new design in accordance with the present invention;

FIG. 2 is a perspective view of the mobile office booth of FIG. 1 shown with the access door open;

FIG. 3 is a front elevation view of the mobile office booth of FIG. 1;

FIG. 4 is rear elevation view of the mobile office booth of FIG. 1;

FIG. 5 is a right side elevation view of the mobile office booth of FIG. 1, the left side elevation view being a mirror image thereof;

FIG. 6 is a top plan view of the mobile office booth of FIG. 1; and,

FIG. 7 is a bottom plan view of the mobile office booth of FIG. 1.

The broken lines in FIGS. 1-7 depict environment only and form no part of the claimed design.
